UNITED STATES PATENT OFFICE.

PETER J. SCHILD, FRANK L. SCHILD, AND CHARLES C. SCHILD, OF IONIA,
MICHIGAN.

HOOF-BOOT FOR HORSES.

SPECIFICATION forming part of Letters Patent No. 392,291, dated November 6, 1888.

Application filed August 16, 1888. Serial No. 282,866. (No model.)

To all whom it may concern:

Be it known that we, PETER J. SCHILD, FRANK L. SCHILD, and CHARLES C. SCHILD, citizens of the United States, residing at Ionia, 5 in the county of Ionia and State of Michigan, have invented new and useful Improvements in Hoof-Boots for Horses, of which the following is a specification.

The invention relates to improvements in 10 hoof-boots for horses, such as are used when treating the hoof to soften or medicate the same; and it consists in the construction and novel combination of parts hereinafter described, illustrated in the drawings, and pointed out in 15 the appended claims.

In the drawings, Figure 1 is a perspective view of a horse-boot embodying the invention. Fig. 2 is a longitudinal sectional view of the same. Fig. 3 is a bottom plan view.

20 Referring to the drawings by letter, A designates the sheet-metal casing of the boot, having a similar shape to the hoof, and sufficiently larger than the same to permit the sponge pad B to be secured within the casing by wires, threads, or other usual and ordinary means.

25 C is an inwardly-curved metal strap extending across the toe portion of the casing A and provided with the upwardly-extending arms e, through openings in which it is secured 30 to the said casing.

D are loops formed on the wires d at the ends of the casing, the said wires being wrapped in the bent and beaded edges of said casing A.

35 E is a strap riveted or otherwise secured to one side of the casing, and with its perforated free end engaged by a buckle, e, fixed upon a strap, e', that is similarly secured to the opposite end of the casing. By means of the strap E and buckle e the casing, with its sponge pad, 40 can be bound tightly on the horse's foot.

45 F is a pad having a leather base, f", and a sponge lining, f, secured to its inner side. The said pad has a longitudinal loop, f", that rides on the strap E, and its front end rests upon the metal strap C about centrally, and is provided with a plate projection, G, riveted between the leather and sponge, and standing out thence between the horseshoe and lower surface of the hoof.

50 H is a strap riveted at its end to one side

of the casing, and having its perforated free end engaged by a buckle, h, on a strap, h', secured to the opposite side of the casing.

I is a rubber tube surrounding the strap H, and bearing between the fetlock and heel of the 55 horse when the hoof-boot is in place.

The boot is strapped on the foot or hoof and used as indicated when necessary, the moisture and heat being retained by the sponge pads.

The purpose of the plate projection G is to 60 engage between the horseshoe and the bottom of the hoof and hold the pad in place and prevent it dropping down. The curved strap C has this function also—viz., to uphold the pad and keep it in place close to the bottom 65 of the horse's hoof.

The present invention is intended as an improvement upon our Letters Patent issued August 21, 1888.

In practice it has been found desirable to 70 secure the sponge to the pad by metal keepers instead of stitching.

Having described our invention, we claim—

1. In a horse-boot, the combination of the metallic sponge-lined casing, the metallic toe-strap secured to the lower edge thereof, the strap E, connecting the rear ends of said casing, and the sponge-lined pad attached to said strap, and with its horizontal portion resting on the metallic toe-strap, substantially as 75 specified.

2. In a horse-boot, the combination of the metallic sponge-lined casing, the metallic toe-strap, the leather strap connecting the ends of the casing, the sponge-lined pad attached to 85 said leather strap, and with its horizontal portion resting on the metallic toe-strap, and the projection G, standing outward from said pad between the hoof and horseshoe, substantially as specified.

3. The combination of the metallic sponge-lined casing, the strap connecting the ends of the same, the metallic toe-strap, the sponge-lined pad attached to the strap connecting the end of the casing, the strap H, and the rubber 95 tube I, surrounding said strap and being between the heel and fetlock of the horse when the boot is in position, substantially as specified.

4. In a horse-boot, the combination of the metallic sponge-lined casing, the leather strap 100

connecting the ends of the casing, the sponge-lined pad attached to said leather strap, and the projection G, standing outward from said pad between the hoof and horseshoe, substantially as specified.

5. In a horse-boot, the combination of the sponge-lined casing, the strap E, connecting the free ends thereof, and the sponge-lined pad F, connected with the strap E, and having a projection, G, engaging between the shoe and the hoof, substantially as specified.

In testimony that we claim the foregoing as our own we have hereto affixed our signatures in presence of two witnesses.

PETER J. SCHILD.

FRANK L. SCHILD.
